UNITED STATES PATENT OFFICE

152,997

DESIGN FOR A MOTOR VEHICLE INSTRUMENT PANEL OR SIMILAR ARTICLE

Edward Macauley, Grosse Pointe Farms, Mich.,
assignor to Packard Motor Car Company,
Detroit, Mich., a corporation of Michigan

Application September 12, 1947, Serial No. 141,334

Term of patent 3½ years

(Cl. D14—6)

To all whom it may concern:

Be it known that I, Edward Macauley, a citizen of the United States, residing at Grosse Pointe Farms, county of Wayne, State of Michigan, have invented a new, original, and ornamental Design for a Motor Vehicle Instrument Panel or Similar Article, of which the following is a specification, reference being had to the accompanying drawing, forming a part thereof.

Fig. 1 is a front elevational view of a motor vehicle instrument panel embodying my new design.

Fig. 2 is a sectional view taken substantially on the line 2—2 of Fig. 1 looking in the direction of the arrows.

Fig. 3 is an end elevational view looking from the right hand end.

The dotted line showing of Fig. 3 is for illustrative purposes only.

I claim:

The ornamental design of a motor vehicle instrument panel or similar article, substantially as shown and described.

EDWARD MACAULEY.
